Primary Examiner — Garth Rademaker*Assistant Examiner* — Aaron C Fowler(74) *Attorney, Agent, or Firm* — IPro, PLLC(57) **CLAIM**

The ornamental design for a vehicle wheel, as shown and described.

DESCRIPTION

FIG. 1 is a front view of a vehicle wheel.

FIG. 2 is a perspective view of the vehicle wheel; and,
FIG. 3 is a left side view of the vehicle wheel.

In the drawings the broken lines depict portions of the wheel that form no part of the claimed design.
